DESIGN FOR A COMBINATION WASHCLOTH AND TOWEL RACK

Norman F. Heym, Wethersfield, Conn.

Application October 9, 1947, Serial No. 141,817

Term of patent 3½ years

(Cl. D33—16)

To all whom it may concern:

Be it known that I, Norman F. Heym, a citizen of the United States, residing at Wethersfield, in the county of Hartford, State of Connecticut, have invented a new, original, and ornamental Design for a Combination Wash Cloth and Towel Rack, of which the following is a specification, reference being had to the accompanying drawing, forming a part thereof:

In the accompanying drawing—

Figure 1 is a plan view of a combination wash cloth and towel rack embodying my new design; Fig. 2 is a front elevation thereof; and Fig. 3 is an end view thereof.

I claim:

The ornamental design for a combination wash cloth and towel rack, substantially as shown.

NORMAN F. HEYM.
